VICTOR YORK, OF WHITTIER, CALIFORNIA

EXPANSIBLE REAMER

Application filed April 30, 1927. Serial No. 187,746.

My invention relates to the art of drilling oil wells, and is particularly applicable to the drilling of oil wells by what is known as the rotary system.

In this system a rotary bit or cutter is secured to the bottom of a string of drill pipe being rotated by a rotary table situated at the surface of the ground. Rotary mud is forced downward through the drill pipe and through openings in the bit to a point near the bottom of the hole, this mud being circulated by means of high-pressure pumps situated on the derrick floor. The mud so circulated serves to carry upward with it the cuttings from the bit, and also serves to cement and mud-up the walls of the hole, so that they will stand without the necessity of casing, it being very common to drill holes in excess of 2000 feet deep by the rotary method without the use of any casing whatever, the rotary mud under pressure serving to hold up the walls of the well and make such drilling possible.

It is not the usual practice in drilling with the rotary method to carry pipe, that is to say, it is not the practice to suspend in the well a string of casing through which the drill pipe projects, this casing being used to hold up the wall of the well, as is the usual practice when drilling a well by the so-called standard or reciprocating system. In some cases, however, it is highly desirable to be able to carry casing, this casing being suspended in the well during the drilling operation and gradually lowered as the drilling progresses.

It is necessary to frequently withdraw the drill pipe for the purpose of replacing or sharpening the bits, and one of the principal values of carrying casing is to prevent the well from caving during the time the drill pipe and bit are being withdrawn. This necessitates the use of a bit which will pass readily through the casing and which will, therefore, drill a hole either smaller or of approximately the same diameter as the inside of the carried casing. Casing cannot pass through a hole of a smaller diameter than its outside diameter, and the practice

of carrying casing in rotary drilling has never been generally adopted.

It is an object of my invention, however, to provide an underreamer which may be collapsed in such a manner as to pass readily through the casing but which automatically expands as it leaves the casing so that it will drill a hole somewhat larger than the outside diameter of the casing.

It is a further object of my invention to provide such an underreamer which can be readily drawn upward into the casing for withdrawal from the well, said underreamer being collapsed for this purpose.

A still further object of the invention is to provide an underreamer in which the reaming elements move bodily from retracted into extended position.

It is also an object of the invention to provide an underreamer in which the reaming elements are locked in retracted position and are released by fluid pressure.

Other objects and advantages of the invention will be made evident hereinafter.

Referring to the drawings:

Fig. 1 is a view illustrating the utility of the invention.

Fig. 2 is an elevational view of the invention partly sectioned, the reaming elements being shown in retracted position.

Fig. 3 is a section taken on the line 3—3 of Fig. 2.

Fig. 4 is a section taken on the line 4—4 of Fig. 2.

Fig. 5 is an elevational view similar to Fig. 2 but showing the reaming elements in extended position.

Fig. 6 is a section taken on the line 6—6 of Fig. 5.

Figs. 7 and 8 are fragmentary sections showing the latch-means of the invention.

The underreamer or reamer 11 of my invention is adapted to be secured to the lower end of a drill column 12 directly above a cutter such as a fish-tail 13. The drill column 12 extends upward through a casing 14 of the well and is supported at its upper end by means of a traveling block 16 which connects to a swivel head 17 thereof. The drill column 12 is rotated by a rotary 18 carried

on the floor of a derrick. Rotary mud is delivered to the fish-tail 13 by means of a pressure pump 20 which is connected to the swivel head 17 by means of a stand pipe 21 and a hose 22.

Referring to Figs. 2 to 5 inclusive, the underreamer 11 has a body 30. The body 30 includes a head 31 having a threaded pin 32, by means of which it is connected to a tool joint 33 provided at the lower end of the drill column 12; a foot-piece 34 having a threaded pin 35 which screws into a coupling 36, by means of which the body 30 is attached to a rotary cutter such as the fish-tail 13; and a plurality of arms 37 which connect the head 31 and the foot-piece 34 together.

In the form of the invention shown, I provide three arms 37 which are arranged symmetrically around the axis of the body 30 which is also the axis of the drill column 12. These arms are near together at the lower end and diverge outward until they are spread apart a maximum distance at their upper ends. The adjacent edges of the arms 37 have grooves 38 which are arranged in planes extending at right angles to a radial line extending from the axis of the body 30 and through the center of the spaces between the grooves 38. The pairs of grooves 38 cooperate to provide ways. As will be obvious from the description the ways diverge upward from the axis of the body 30. The lower ends of the ways are closed, whereas the upper ends thereof are opened so that carriers 40 may be extended into them.

The carriers 40 have tongues 41 which project into the grooves 38 which cooperate to provide the ways. The carriers are adapted to slide along the ways but are prevented from being removed from place by means of a retainer 42. The retainer 42 is placed on the head 31 and is retained thereon, since it is provided with an annular in-turned lip 43 which is clamped between the head 31 and a lower face of the tool joint 33. The retainer 42 has arms 45, each of which extends so as to close the upper ends of the ways. Each arm 45 has a face 46 which is adapted to be engaged by an upper face 73 of each of the carriers 40 when each carrier is moved into its extreme upper position. The carriers 40 include shafts 47 which extend parallel to the ways in which they are carried and on which reaming elements 48 are supported, these reaming elements 48 consisting of cutters having serrations and being adapted to rotate.

The head 30 has a central vertical opening 50, and the foot-piece 34 has a vertical central opening 51, these openings being aligned. Extending through these openings and through the space inside the arms 37 is a circulation tube or conduit 52. The lower end of the conduit 52 is threadedly secured

in the opening 51 and the upper end thereof has a seal formed around it by a packer 54. The conduit 52 conducts rotary mud from the drill column 12 to the fish-tail 13.

Surrounding the conduit 52 and adapted to slide thereon is a collar 56. This collar 56 is provided with ears 57 to which links 58 are pivoted by shafts 59. The upper ends of the carriers 40 have the outer ends of the links 58 pivoted thereto by pivot-shafts 60. Surrounding the conduit 52 below the collar 56 is a coil-spring 61, the lower end of which rests in a cavity 62 of the foot-piece 34 and the upper end of which engages the collar 56. The purpose of the coil-spring 61 is to tend to urge the collar 56 from the position shown in Fig. 2 into the position shown in Fig. 5, in which position the faces 73 of the carriers 40 engage faces 46 provided by the retainer 42. In view of the fact that the carriers move outward when they move upward it is necessary to provide the links 58 as connecting means so that the outward movement will be provided for.

During the time that the underreamer is lowered through the casing 14, the reaming elements must be retained in retracted position so that they will not engage the casing and become wedged. I provide a lock mechanism which is illustrated best in Figs. 7 and 8. The conduit 52 is provided with a small opening 64 which is in alignment with a notch 65 of the collar 56 when the collar 56 is in the position shown in Figs. 2 and 7. Pivoted on a shaft 66 which is inside the conduit and directly below the opening 65 is a latch-member 67. The latch-member 67 has an arm 68 which extends upward and is provided with a hook 69 at its upper end. When the latch-member 67 is in latching position, the hook 69 extends through the opening 64 and into the notch 65, locking the collar 56 in the position shown in Figs. 2 and 7. Extending substantially at right angles to the arm 68 is a plate 70 which has a small opening 71 and which is slightly smaller in diameter than the opening through the conduit 52. When the latch-member 67 is in latching position, the plate 70 closes the opening of the conduit 52. The latch-member 67 may be moved into unlatched position as indicated by dotted lines 72 by starting the pressure-pump 20. When the pressure-pump is started, mud is forced downward through the drill column and through the conduit 52. The pressure against the plate 70 swings the latch-member 67 from latched position into the position indicated by dotted lines 72 and releases the collar 56. When the collar 56 is released, the coil-spring 61 forces it upward and the reaming elements 48 are moved into reaming positions.

It will be noted that the reaming elements when in collapsed position are included within a circle which is of a smaller diameter

than the casing 14, but when they are in extended position the outer edges touch a circle which is of a larger diameter than the outer diameter of the casing 14. It will be seen then that the underreamer may be readily lowered through a casing, and after it has passed from the lower end thereof may be actuated so that the reaming elements are moved into extended position, by merely 5 starting the pressure-pump 20. In view of the fact that when the reaming elements are moved downward they are collapsed, the underreamer may be pulled upward through the casing, this being because the engagement of the reaming elements 48 with the casing moves them downward so that they are retracted and may pass through this casing.

The important features of the invention 20 may be briefly enumerated as follows: The provision of reaming elements which are moved bodily from retracted into extended position is important to the invention. The means for moving the reaming elements into 25 extended position is important because of its reliability and simplicity of construction.

The locking means shown is satisfactory, but it should be understood that other locking means may be provided if desired.

30 The term "underreamer" tends to convey the impression that my invention is solely for the purpose of underreaming for a well casing which is advanced downward into a well as the drilling progresses. I 35 wish to impress, however, that my invention is equally useful as a reamer which operates continuously with a bit. As an example, in some wells a short surface casing which extends through the stovepipe casing, is employed for preventing a caving-in of the 40 softer strata near the surface. In removing or inserting the bit and reamer, they must pass through this surface casing. My invention is very suitable for use under these 45 conditions, owing to the novel means for locking the cutter elements in contracted position while the bit passes through the casing.

I claim as my invention:

1. A reamer comprising: a body adapted to 50 be secured to a drill column, said body having a way, said way extending non-parallel to the axis of said column; a carrier adapted to travel along said way; a reaming element carried by said carrier; and a fluid-operated 55 latch for holding said carrier in normal retracted position.

2. A reamer comprising: a body adapted to 60 be secured to a drill column, said body having a way, said way extending non-parallel to the axis of said column; a carrier adapted to travel along said way; a reaming element carried by said carrier; an operating member 65 slidale relative to said body; a thrust link connecting said carrier and said operating member; and urging means for urging said

operating member to slide relative to said body.

3. A combination as defined in claim 2 also having a releasable latch for holding said operating member in such a position that said carrier and reaming element are retained in retracted position, said latch being releasable irrespective of the position of said drill column.

4. A reamer comprising: a body adapted to be secured to a drill column, said body having a way, said way extending non-parallel to the axis of said column; a carrier adapted to travel along said way; a reaming element carried by said carrier; an operating member slidale relative to said body; connecting means for connecting said carrier and said operating member; urging means for urging said operating member to slide relative to said body; and a fluid-operated latch for retaining said operating member in such a position that said carrier and reaming elements are retained in retracted position.

5. A combination as defined in claim 1 in which said reaming element rotates on an axis parallel to said way.

6. A reamer comprising: a body adapted to be secured to a drill column, said body having a plurality of ways extending non-parallel to the axis of said column; a carrier adapted to travel along each of said ways; reaming elements carried by said carriers; a collar slidale relative to said body; a spring for urging said collar upward; links connecting said collar and each of said carriers; and a releasable latch engaging said collar to hold said spring in compressed position.

7. A reamer comprising: a body adapted to be secured to a drill column, said body having a plurality of ways extending non-parallel to the axis of said column; a carrier adapted to travel along each of said ways; reaming elements carried by said carriers; a fluid conduit in said body; a collar slidale on said conduit; a linkage connecting said collar and said carriers; a resilient means for urging said reaming elements into extended position; and a latch engaging said collar to hold said resilient means in compressed position, said catch being fluid operated to release said collar.

8. A combination as defined in claim 7 in which said latch comprises a plate pivotally secured inside said fluid conduit and including a hook extending through said conduit to engage said collar.

In testimony whereof, I have hereunto set my hand at Los Angeles, California, this 20th day of April, 1927.

VICTOR YORK. 125
